UNITED STATES PATENT OFFICE.

MORRIS PESSIN, OF NEW YORK, N. Y.

WIRE-STRIPPING MACHINE.

1,052,271.

Specification of Letters Patent. Patented Feb. 4, 1913.

Application filed January 30, 1912. Serial No. 674,380.

To all whom it may concern:

Be it known that I, MORRIS PESSIN, a subject of the Czar of Russia, and a resident of the city of New York, borough of Brooklyn, in the county of Kings and State of New York, have invented a new and Improved Wire-Stripping Machine, of which the following is a full, clear, and exact description.

This invention relates to improvements in wire stripping machines and has for an object to provide an improved structure for removing one or more layers of insulation from any desired length of wire.

Another object of the invention is to provide an improved structure which will straighten lengths of wire, sever the insulating matter thereon, and then remove the severed portions, each independent part of the insulation being removed to different receptacles.

In carrying out the objects of the invention, a wire straightening mechanism is provided which straightens and feeds the wire into a guiding tube formed with slits through which knives project for cutting or slitting the insulation on the wire longitudinally. One of the coats of insulation is engaged by a pair of rollers, and removed from the wire as the rollers progress through the machine, and the other insulation is removed by a second pair of rollers which are assisted by a guiding member which causes the insulation to positively leave the wire. The wire is then guided to a drum upon which it is wound so that the wire leaving the machine is wound on the retaining drum and the various layers of insulation are removed and positioned in various independent receptacles provided therefor.

A practical embodiment of the invention is represented in the accompanying drawings forming a part of this specification, in which similar characters of reference indicate corresponding parts in all the views.

Figure 1 is a top plan view of an embodiment of the invention; Fig. 2 is a side view of the structure shown in Fig. 1; Fig. 3 is a longitudinal sectional view through Fig. 1, approximately on the line 3-3; and Fig. 4 is an enlarged detail fragmentary view approximately on the line 4-4 of Fig. 3.

Referring to the accompanying drawings by numerals, 1 indicates a supporting framework of any desired kind and provided with any desired number of longitudi-

dinal members and transverse members, as occasion may require, for supporting the various moving parts of the device. Arranged at one end of the framework is a receptacle 2 of any desired kind, adapted to contain the wire before the insulation is removed, and from which the wire is fed into the machine. At the opposite end of the receptacle 2 is a drum 3, upon which the stripped wire 4 is wound. When the wire 5 leaves the receptacle 2 the same passes between rollers 6 and from thence upward and over guiding rollers 7, 8 and 9. Between the rollers 7 and 8 is a resiliently positioned roller 10, and between the rollers 8 and 9 is a roller 11 held resiliently against the wire 5.

The rollers 6 and 7 to 11 inclusive, are designed to act as straightening means for straightening the wire 5 previous to its entrance into a guiding tube 12. The guiding tube 12 is formed with slots 13 and 14 through which project the knives 15 and 16. The knives 15 and 16 are designed to cut entirely through all of the insulation on the wire, but not to cut into the interior of the stripped wire 4. Wires 4 and 5 are the same except that one is shown with insulation and the other without. The guiding tube 12 is supported by cross bars 17 and 18 held in place by suitable bolts 19 projecting through slots 20 formed in a bracket 21 forming part of the framework 1. The guiding tube 12 is made adjustable so that larger or smaller tubes may be used according to the size of wire being operated upon. The knife 15 is preferably mounted so as to not be adjustable vertically, but the knife 16 may be freely adjusted vertically as the same is supported by an arm 22 pivoted at 23 and held in any adjustable position by an adjusting member 24. If it is desired to operate upon a larger wire than wire 5, a larger tube 12 is placed in position and the tube is raised to the desired extent so that the knife 15 will not injure the wire. The knife 16 is then adjusted by the member 24 so that the knife 15 will not injure the wire. The knives 15 and 16 are rigidly connected with shafts 25 and 26 so that whenever the gear wheels 27 and 28 turn, the knives will also turn, the gear wheels 27 and 28 being keyed or otherwise secured to the shafts 25 and 26. The shaft 25 carries at its outer end a pulley 29 which accommodates a belt 30 fitting over a driving pulley 31 rigidly secured to

the shaft 32. The shaft 32 has rigidly connected therewith a drum 3 and a power pulley 33. The power pulley 33 receives power from any suitable source through a belt 34.

As clearly shown in Figs. 1 and 2, the arms 22 are rigidly connected with the shaft 32 which carries an adjusting arm 35 rigidly secured thereto and adjusted by the 10 adjusting member 24. By these means the knife 16 may be raised and lowered whenever desired. In Fig. 1 a structure accommodating two knives is shown, but it will be evident that one, two, or more knives 15 may be used without departing from the spirit of the invention.

After the wire 5 has passed through the guiding tube 12, the outer insulation is passed over the roller 36 and downward 20 between rollers 37 and 38 into a receptacle 39. The outer layer of insulation is usually formed of fabric of some kind so that by removing the outer layer as just described, the same is segregated from the 25 inner layer 40 which is usually of rubber or some insulating gum mixture. The insulating layer of rubber 40 engages a guiding member 41 which is provided with a tapered aperture 42 for accommodating 30 the stripped wire 4. The smaller end of the aperture 42 is designed to be only sufficiently large for accommodating wire 4 so that the insulation 40 will move downward over the inclined surface 43 and will finally 35 pass between rollers 44 and 45 and from thence into a box or receptacle 46. The rollers 37 and 38 are designed to pull somewhat against the outer insulation 47, while the rollers 44 and 45 pull against the inner 40 insulation 40 so as to cause a proper removal thereof from the wire in case the same are inclined to stick. The guiding member 41 is held adjustably in position by bolts 48 passing through suitable slots 45 49 in the cross brace 50. This adjustment is desirable in order to accommodate larger or smaller wires. It will of course be understood that the guiding member 41 must be provided with an aperture 42 of the proper 50 size for any particular wire.

The rollers 44 and 45 and also the rollers 37 and 38 are connected together by a suitable train of gearing so as to operate together. The roller 38 is connected through 55 an idler 38' to the gear wheel 28 so that power is transmitted to the respective rollers for rotating the same as well as to the knives 15 and 16.

Having thus described my invention, I 60 claim as new and desire to secure by Letters Patent:—

1. In a wire stripping machine, a pair of oppositely disposed co-acting rotary knives, a tube slotted on opposite sides arranged so 65 that the knives will project through said

slots into the tube, means for directing an insulated wire through said tube whereby the insulation thereof will be slit, means for pulling the insulation from the wire after the insulation has been slit by said knives. 70

2. In a wire stripping machine, a pair of oppositely disposed rotating knives, a guiding tube arranged between said knives and formed with slits for permitting the knives to project into the tube whereby when a wire having insulation thereon is passed through the tube the insulation thereon will be slit longitudinally, and means for removing the insulation after the same has been slit. 75

3. In a wire stripping machine, a pair of oppositely disposed co-acting rotary knives, a tube slotted on opposite sides arranged so that the knives will project through the slots in the tube, and means for directing an insulated wire through said tube whereby said knives will slit the insulation on the wire longitudinally. 80 85

4. In a wire stripping machine, a pair of rotating oppositely disposed co-acting knives, means for forcing a wire having insulation thereon past said knives in such a direction as to permit said knives to slit the insulation longitudinally, means for stripping the insulation from the wire after the insulation has been slit, and means for guiding the wire to a point of discharge. 90 95

5. In a wire stripping machine, a pair of co-acting knives, means for guiding a wire past said knives so that the knives will slit 100 the insulation on the wires longitudinally, means for straightening and guiding an insulated wire to said knives, and means for separately removing the stripped wire and the insulation. 105

6. In a wire stripping machine, a pair of rotating knives, a tube for guiding an insulated wire past said knives so that the knives will slit the insulation longitudinally, means for adjusting said knives in order to 110 regulate their distance apart whereby different sized wires may be accommodated, means for adjusting the position of the guiding tube, and a plurality of means for disposing of the stripped wire and insulation after the insulation has been slit. 115

7. In a wire stripping machine, a pair of oppositely disposed co-acting rotary knives, a tube slotted on opposite sides arranged so that the knives will project through said slot into the tube, means for directing an insulated wire through said tube whereby said knives will slit the insulation on the wire longitudinally, a pair of rollers engaging the insulation and pulling the same from 120 the wire after the insulation has been cut by said knives, means for guiding the insulation to said rollers, and means for guiding the stripped wire to a discharge point. 125

8. In a wire stripping machine, means for 130

slitting the insulation of a wire longitudinally, independent means for removing each layer of insulation from said wire, and means for guiding the wire to a point of discharge.

9. In a wire stripping machine, means for slitting a wire insulation made of a gummed substance and a fabric substance, a pair of rollers for removing the fabric substance from the wire, means for guiding the fabric substance to said rollers, a second pair of rollers for removing the gummed substance

from said wire, and a guiding and substantially feeding structure for guiding the gummed substance to said second mentioned rollers, and means for guiding the stripped wire to a point of discharge. 15

In testimony whereof I have signed my name to this specification in the presence of two subscribing witnesses.

MORRIS PESSIN.
